(57) **CLAIM**

The ornamental design for a support plate, as shown and described.

DESCRIPTION

FIG. 1 is a front top perspective view of my support plate of my present invention.

FIG. 2 is a bottom rear perspective view of FIG. 1.

FIG. 3 is a top plan view of FIG. 1.

FIG. 4 is a bottom pan view of FIG. 1.

FIG. 5 is a right side elevation view of FIG. 1.

FIG. 6 is a left side elevation view of FIG. 1.

FIG. 7 is a front elevation view of FIG. 1; and,

FIG. 8 is a rear elevation view of FIG. 1.

The dash-dash lines represent portions of the support plate that form no part of the claimed design.
